D. COLLINS

CIGARETTE HOLDER

Filed Feb. 2, 1924

FIG. 1

FIG. 2

Inventor

Douglas Collins

Chas. K. Davies

Attorney

UNITED STATES PATENT OFFICE.

DOUGLAS COLLINS, OF SALISBURY, NORTH CAROLINA.

CIGARETTE HOLDER.

Application filed February 2, 1924. Serial No. 690,236.

To all whom it may concern:

Be it known that I, DOUGLAS COLLINS, a citizen of the United States of America, residing at Salisbury, in the county of Rowan 5 and State of North Carolina, have invented certain new and useful Improvements in Cigarette Holders, of which the following is a specification.

My present invention relates to improvements in cigarette holders of that type embodying a combined cigarette retainer and an ejector for the butt end of the consumed cigarette. While I have illustrated the device in the drawings, and shall hereinafter 10 refer to it in the specification and claims as a cigarette holder, it will be understood that my invention contemplates other uses, as for instance it may readily be adapted for a cigar holder.

The primary object of my invention is the provision of an article of manufacture of this character in which the duct in the holder may be kept clear at all times for the passage of smoke, or for cleaning, and 15 which embodies a compactly arranged combined retainer and ejector that is simple in construction and operation, durable, and which may be manufactured at comparatively low cost of production.

In the accompanying drawings I have illustrated one complete example of the physical embodiment of my invention conforming to the standard type of cigarette holders, in which the parts are combined 20 and arranged in accordance with the best mode I have thus far devised for the practical application of the principles of my invention. Changes and alterations may be made in the exemplified structure, within 25 the scope of my claims, without departing from the spirit of my invention.

Figure 1 is an exterior view of the tubular holder containing a cigarette which is shown in dotted lines.

Figure 2 is a longitudinal sectional view of the holder with a cigarette retained therein.

Figure 3 is a longitudinal sectional view of the holder showing the position of the ejector when not retaining a cigarette.

Figure 4 is a transverse sectional view at

line 4—4 of Figure 1, said view being on an enlarged scale.

In carrying out my invention I utilize a cigarette holder conforming to the usual 55 type of such articles, which is indicated as a whole by the numeral 1, and which may be composed of acceptable material as amber or other well known materials for this purpose. The holder is provided with the usual 60 socket head 2 for the reception of one end of the cigarette C, and the usual smoke passage or duct 3 extends throughout the length of the holder.

The mouth piece 4 and head 5 thereon are 65 of the customary shape and size for convenience of the smoker.

The combined retaining and ejecting device is fashioned of a single piece of resilient metal or spring wire possessing the required 70 rigidity, and is slidable longitudinally of the holder for ejecting the cigarette butt.

At one end of this combined retainer and ejector is fashioned a hook shaped head 6 75 over which the cigarette end is to be forced as it is inserted in the socket-head of the holder, and the pressure applied causes the head 6 as it passes into the cigarette end, to force the tobacco radially or spread it laterally from the center of the cigarette 80 against the walls of the socket head. In this manner the cigarette end is forced against the walls of the socket head for the purpose of causing such frictional engagement therewith that the cigarette is retained 85 in the head of the holder.

At a suitable intermediate point the slideable retainer-ejector, which is of resilient material, is fashioned with an offset portion 90 7 designed for frictional engagement with the interior walls of the smoke duct 3. It will be apparent that the utility of this offset portion lies in its engagement with the interior face of the tubular holder to maintain the slideable device in normal position, and yet permit sliding movement of the device when the required force is applied as for ejecting purposes.

The body of the ejector extends longitudinally 100 through the tubular holder back from the socket head, and at its inner end the

2
ejector is fashioned with a bend 8 which merges into a short arm 9 formed approximately parallel with the body of the ejector from which it is spaced slightly apart.

5 The short arm of the ejector is fixed in suitable manner to a slide sleeve 10 reciprocable on the exterior of the holder.

If desired and to accommodate the bend 8 of the arm and ejector, the mouth piece 10 of the holder may be notched or cut out as at 11, said notch being located at one side of the end of the mouth piece and merging with the duct 3 of the holder.

The depth of the notch 11 may be determined by the thickness of the ejector and the exterior shape of the tubular holder, and in some instances the holder on an exterior face of the mouth piece, may be grooved to receive the arm of the ejector.

20 The slide sleeve 10 which encases the holder conforms to its exterior shape. In the illustrated form of the invention herein the tubular holder is shown as rectangular in cross section with a cylindrical bore or duct, and the sleeve therefore has four flattened sides by means of which the sleeve is prevented from turning on the holder and is also guided to move in alignment with the longitudinal bore of the holder when the 25 ejector is reciprocated.

Sufficient frictional engagement between the sleeve and holder is present to hold the sleeve in stable relationship and in normal position.

35 At the notch 11 the mouth piece of the holder is provided with a shoulder 12 to obstruct the bend 8 and prevent excessive movement of the retainer-ejector toward the front of the holder, but the sleeve is free to be moved toward the mouth piece without obstruction other than the frictional engagement of the sleeve and holder and the offset portion 7 of the ejector with the interior of the tubular holder. Thus the ejector and 40 sleeve may be entirely detached from the holder if necessary for the purpose of cleansing both the ejector and the holder.

The slide sleeve 10 and the arm 9 may be made of polished metal, and ornamented as 50 desired to insure a neat and attractive appearance.

As seen in Figure 3 the body of the ejector is of angular shape and out of alignment with the longitudinal bore or duct of the tubular holder. As the cigarette end is slipped over the head of the ejector and the cigarette is inserted and located in the socket-head of the holder the headed end of the ejector is placed under tension for the purpose of retaining the cigarette as described.

When properly retained in the socket head, the cigarette or the holder may be tapped for the purpose of dislodging ashes from the burnt end of the cigarette without likelihood 65 of the latter being displaced from its socket

head, for it will be apparent that the co-action of the ejector-head, which is under tension, and the walls of the socket-head will rigidly hold the cigarette end in the socket head of the holder.

To eject a cigarette butt it is obvious that the finger and thumb which grasp the slide sleeve may push the sleeve toward the mouth piece thus bodily moving the ejector longitudinally of the tubular holder. As the 75 cigarette is prevented from movement, the ejector head is withdrawn therefrom. Then with a quick forward movement of the slide sleeve toward the socket-head, the freed ejector head, which at this time is out of 80 alignment with the longitudinal center of the tubular holder, contacts with the cigarette butt to force the same from the holder.

While I have exemplified the invention herein with a rectangular slide sleeve to conform to the exterior of the tubular holder, it will be apparent that if a round, triangular, or other shape in cross section is adopted for the holder the slide sleeve will conform thereto, and it will also be obvious that the material of which the ejector is made may be shaped to different forms in cross section. These and other similar changes I contemplate in the physical embodiment of my invention and may be made 95 without departing from the scope of my appended claims.

Having thus fully described my invention, what I claim as new and desire to secure by Letters Patent is—

1. The combination with a tubular holder having a socket head, of a longitudinally slidable ejector having a retaining-head adapted to project into the end of a cigarette and co-act with the socket head for 105 retaining the cigarette.

2. The combination with a tubular holder having a socket-head, of a longitudinally slidable ejector having an exterior integral arm, actuating means on said arm, and a head on said ejector to project into an end of a cigarette and co-act with the socket head for retaining the cigarette.

3. The combination with a tubular cigarette holder having a socket-head, of a longitudinally slidable ejector adapted to project into a cigarette end and having a portion for frictional contact with an interior wall of the holder.

4. The combination with a tubular cigarette holder having a notch and a socket-head at opposite ends, of a slidable ejector having a frictional portion engaging an interior wall of the holder, a rigid arm on the ejector having a bend in said notch, and a head on said ejector adapted to project into a cigarette end and co-act with the socket-head to retain the cigarette.

5. The combination with a cigarette holder having a notch and a socket-head at

opposite ends, of a slidable ejector having a portion for frictional engagement with the interior of the holder, a rigid arm on the ejector and a connecting bend located in said notch, a slide sleeve exterior of the holder and secured to said arm, and a head on the ejector adapted to project into a cigarette and co-act with the socket-head for retaining the cigarette end in the socket head.

10 6. The combination with a tubular cigarette holder of a slidable, resilient ejector adapted to frictionally engage the interior wall of the holder, and tension actuated means on the end of the ejector adapted to project into a cigarette end and co-act with the tubular holder for retaining the cigarette in the holder.

15

In testimony whereof I affix my signature.

DOUGLAS COLLINS.
